HUMIDIFIER

Ralph C. Kuehler, Humboldt, Iowa

Application October 18, 1938, Serial No. 235,658

2 Claims. (Cl. 261—107)

This invention relates to a humidifier designed primarily for use in incubators, or places where in it is desirable to add humidity to the air of an incubator or cabinet to maintain the eggs 5 or articles contained therein, moist.

An important object of the invention is to provide a humidifier of this character which is self-priming and quick acting, to the end that moisture will be added to the air almost immediately upon the starting of the fan, forming a part of the humidifier.

Another object of the invention is to provide a humidifier wherein the amount of humidity may be regulated at the will of the operator to the end that an accurate amount of humidity may be added to the air for the efficient operation of the device with which the humidifier is used.

With the foregoing and other objects in view, which will appear as the description proceeds, 20 the invention resides in the combination and arrangement of parts and in the details of construction hereinafter described and claimed, it being understood that changes in the precise embodiment of the invention herein described, may be made within the scope of what is claimed, 25 without departing from the spirit of the invention.

Referring to the drawing:

Figure 1 is an elevational view of an incubator, the central portion thereof being broken away to illustrate the humidifier and fan used in connection therewith.

Figure 2 is a transverse sectional view through the humidifier, disclosing the fabric material as 35 extended under the pressure of the air from the fan.

Figure 3 is a transverse sectional view taken at right angles to Figure 2.

Figure 4 is an enlarged sectional detail view 40 through the fabric clamping member.

Referring to the drawing in detail, the reference character 5 designates the body portion or cabinet of an incubator of well known construction. The humidifier, forming the essence of the 45 present invention, includes a shallow pan indicated generally by the reference character 6, the pan being supported within the central portion of the cabinet 5, as clearly shown by Figure 1 of the drawing, as by means of the brackets 7 which 50 are suspended from the ceiling of the compartment 8 of the incubator. Thus it will be seen that due to this method of supporting the pan 6, the pan may be readily and easily removed and replaced, should it be desired to clean or repair 55 the pan.

The reference character 9 designates a rod that extends across the bottom of the pan 6, in spaced relation therewith, and this rod provides means for connecting one end of the plate 10 to the bottom of the pan 6.

The plate 10 is shown as having one end thereof extended upwardly as at 11 to restrict movement of the plate with respect to the rod 9, while the opposite end of the plate is bent upwardly as at 12 to fit under the keeper 13 that is secured to one end of the pan.

Openings 14 are punched from the plate 10, portions of the material of which the plate is constructed, adjacent to the openings being forced outwardly, providing spurs 15. These 15 spurs 15 are pressed against the length of cloth material indicated at 16, and which is positioned within the pan, under the plate 10, to secure the cloth material against movement under the plate 10. The cloth material 16 is constructed preferably of terry cloth material because of the nature of this particular type of cloth which lends itself readily to capillary attraction.

As clearly shown by Figure 2 of the drawing, the length of cloth material 16 is such that it 25 extends beyond the sides of the pan 6, appreciable distances, so that the extended ends of the cloth 16 will be engaged by the air directed upwardly to the fan and cloth material, from the fan 17 supported at the bottom of the compartment 8.

Water is supplied directly onto the plate 10, in drops, from the pipe 18, which has its upper end extending into the pan 19 that provides the supply tank for the water used in humidifying the 35 air circulated through the incubator.

From the foregoing it will be seen that due to the construction of the pan, and because the sides of the pan are substantially short, the device will be self-priming and quick acting.

The water drops onto the plate 10, from where it passes through the openings of the plate, contacting with the cloth material 6. Due to capillary attraction, the water passes upwardly throughout the length of the cloth material 16, 45 the ends of the cloth material being forced outwardly due to the current of air directed upwardly thereto by the fan 17. By reducing the quantity of moisture passing into the fan, the humidity may be regulated to meet various requirements, and the moistening of the ends of the cloth material 16, due to capillary attraction, will be exceptionally rapid.

What is claimed is:

1. A humidifier comprising a body portion hav- 55

- ing a central vertical passageway, an upwardly directed fan mounted at the bottom of the passageway, a tray suspended at the top of the passageway, a length of fabric material supported in the tray, the ends of the fabric material hanging over the sides of the tray and being free to swing upwardly under the action of the air from the fan, means for directing liquid to the tray to be absorbed by said fabric material, and said fan adapted to direct a blast of air against the overhanging ends of the fabric material forcing moisture from the fabric material and directing the moisture upwardly through the passageway.
2. A humidifier comprising a body portion having a central vertical passageway, a fan mounted at the bottom of the passageway and adapted to direct air upwardly through the pas-

sageway, a tray suspended at the top of the passageway, a length of fabric material supported in the tray adjacent to the center of the tray for holding the fabric material against the bottom of the tray, portions of the fabric material being inclined and extended over the sides of the tray, the ends of the fabric material adapted to hang over the sides of the tray, means for directing liquid to the tray to be absorbed by the fabric material, and said fan adapted to direct a blast of air against the overhanging ends of the fabric material, spreading the overhanging ends to horizontal positions whereby the moisture in the fabric material may be picked up by the air blast and directed through the passageway.

RALPH C. KOCHER.
